US0D1104249S

(12) **United States Design Patent** (10) Patent No.: **US D1,104,249 S**
(45) Date of Patent: ** Dec. 2, 2025

(54) **FRAME**

(71) Applicant: **DCSTAR INC**, New York, NY (US)

(72) Inventor: **Ligui He**, New York, NY (US)

(73) Assignee: **DCSTAR INC**, New York, NY (US)

(**) Term: **15 Years**

(21) Appl. No.: **29/959,443**

(22) Filed: **Aug. 26, 2024**

Related U.S. Application Data

(63) Continuation of application No. 29/861,121, filed on Nov. 28, 2022, now Pat. No. Des. 1,047,133.

(30) **Foreign Application Priority Data**

Primary Examiner — Daniel J Domino

Assistant Examiner — Lee D. Starr

(57) **CLAIM**

The ornamental design for a frame, as shown and described.

DESCRIPTION

FIG. 1 is a front view of a frame showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a rear perspective view thereof.

The broken lines depict portions of the frame that form no part of the claimed design.

1 Claim, 8 Drawing Sheets
